UNITED STATES PATENT OFFICE.

JOHN M. GERHARDT, OF HIGHMORE, SOUTH DAKOTA.

VENDING APPARATUS.

Application filed July 23, 1925. Serial No. 45,713.

This invention appertains to liquid dispensing apparatus and the primary object of the invention is to provide novel means for dispensing soft drinks in a sanitary and attractive manner to the trade.

5 Another object of the invention is the provision of a novel device for dispensing soft drinks in which the container for the drinks can be arranged at a point remote from the 10 counter or bar and novel means for maintaining the liquid being dispensed at a cool temperature with a minimum amount of expense for ice or other refrigerant.

15 A further object of the invention is to provide novel means for displaying the drinks to be dispensed, the means being so arranged as to allow a number of different drinks to be displayed in a relatively small space, the entire device permitting customers 20 to be served with dispatch and with a minimum amount of labor.

25 A still further object of the invention is to provide a soft drink dispensing device of the above character, which will be durable and efficient in use, one that will be simple and easy to manufacture and one which can be placed upon the market at a small cost.

With these and other objects in view, the 30 invention consists in the novel construction, arrangement and formation of parts, as will be hereinafter more specifically described, claimed, and illustrated in the accompanying drawings, in which drawings:

35 Figure 1 is a diagrammatic view of the improved liquid dispensing apparatus, showing the bar in rear elevation.

Figure 2 is a side elevation of one soft drink receiving container,

40 Figure 3 is a fragmentary section through one end of the bar illustrating the novel means for displaying the drinks being dispensed,

45 Figure 4 is a detail plan view of the fragment dispensing apparatus showing a part of the means utilized for displaying the soft drinks,

50 Figure 5 is a horizontal section taken on the line 5—5 of Figure 1 looking in the direction of the arrows illustrating the novel means employed for cooling the drinks being dispensed,

55 Figure 6 is a transverse section taken on the line 6—6 of Figure 1.

Referring to the drawings in detail, wherein similar reference characters desig-

nate corresponding parts throughout the several views the letter A generally indicates the improved dispensing apparatus, which as shown is utilized for dispensing four different kinds of drinks, but it is to be understood that any number of different kinds of drinks can be dispensed by simply adding more dispensing containers and coils which will be hereinafter described. The improved 60 dispensing apparatus A comprises a bar or counter 10 including a top wall or slab 11 over which the drinks are adapted to be dispensed.

At each end of the slab or top 11 can be 70 placed metallic plates 12 and 13 which can be countersunk within the upper face of the said slab or top 11. The plates 12 have formed therein any number of depending wells 14 which are fitted within suitable 75 openings 15 placed in the top or slab. These wells 14 are adapted to receive the threaded necks 16 of the display globes or bulbs 17 for the liquid. These bulbs are formed of clear transparent glass and the purpose 80 thereof will be hereinafter more fully described.

Arranged at a point remote from the bar or dispensing counter 10 are arranged the 85 containers 20 for the drinks to be dispensed and there can be as many of these containers as desirable. The said container 20 can be made of any desired material, such as glass, porcelain, copper or the like and are provided at their sides with removable covers 90

21 to premit the filling of the said container with the desired liquid. Leading from the bottom of the containers and out of the tops thereof are the feed pipes 22 for the liquid and these pipes extend through 95 the wells 14 into the globes or transparent bulbs 17 and terminate adjacent to the upper ends thereof. The liquid in containers 20 is adapted to be forced therefrom under pressure and a suitable compressed air tank 23 can be provided for that purpose. A header 100 24 leads from the compressed air tank over the top of the containers 20 and suitable feed nipples 25 leads from the header pipe 24 into the tops of the containers. It is obvious 105 that the compressed air will force the liquid through the pipe 22, which as stated extends adjacent to the bottoms of the container.

Arranged under the counter or bar 10 is a 110 suitable box or receptacle 30 which can be formed of block tin or the like and this box is supported by suitable legs 31. Disposed

within the box at the lower end thereof are a plurality of cooling coils 32 through which the liquid being dispensed is adapted to flow and feed pipes 33 extend from the bottoms 5 of the wells 14 to the coils. The opposite ends of the coils have connected thereto dispensing pipes 34 which lead to the rear wall of the box to suitable dispensing spigots or faucets 35. These spigots or dispensing 10 faucets 35 are carried by the rear wall of the box adjacent to the upper end thereof.

Arranged below the spigots or dispensing faucets 35 is arranged an inclined trough 36 for receiving the drip from the faucets and a suitable drain pipe 37 is connected 15 with one end thereof.

The box 30 is adapted to receive ice in order to effectively cool the drinks being dispensed and in order to protect the coils 20 against injury by the ice placed in the box suitable spaced supporting bars or slats 38 are arranged within the box directly above the coils. On each side of the trough 36 and the spigots 35 the box is provided with doors 25 39 and by raising the said doors, blocks of ice can be readily placed upon the supporting bars 38.

The bottom wall of the box is preferably shaped so as to facilitate the draining of 20 the melted ice water therefrom and a suitable pipe 40 is carried by the lower wall and leads to the drain pipe 37.

In use of the improved apparatus, it can be seen that the liquid from the tanks is 35 first elevated to the globes or transparent bulbs 17, where the same can be readily seen by the trade after which the liquid will flow through the coils and become cooled

by the ice in the box and then can be readily dispensed from the spigots or faucets 35. 40

From the foregoing description, it can be seen that I have provided a novel soft drink dispensing apparatus of an exceptionally simple character in which the drinks can be positively maintained in a sanitary condition and permit the ready dispensing thereof. 45

Changes in details may be made without departing from the spirit or the scope of this invention, but,

What I claim as new is:—

1. In a beverage dispensing apparatus, a display counter, metallic plates carried by the counter provided with depending wells, transparent display bulbs provided with reduced threaded necks fitted into said wells, containers for the beverage, feed pipes leading into the bottom of the containers through the wells into the upper ends of the display bulbs, means for forcing the beverage from the containers, pipes leading from the bottom of the wells, spigots connected with said last mentioned pipes, and means for cooling the beverage prior to delivery of the beverages to the spigots. 55

2. In a vending dispensing apparatus, a display counter having a well in the upper face thereof, a transparent display bulb having a portion thereof fitted in said well, a container for the beverage to be dispensed, a feed pipe leading from the container to 70 the display bulb, a dispensing pipe connected with the well, and a spigot connected with the last mentioned pipe.

In testimony whereof I affix my signature.

JOHN M. GERHARDT.
